UNITED STATES PATENT OFFICE.

WALTER M. COX, OF JERSEY CITY, NEW JERSEY.

GAME APPARATUS FOR PLAYING INDOOR FOOTBALL.

Application filed October 15, 1924. Serial No. 743,711.

To all whom it may concern:

Be it known that I, WALTER M. Cox, a citizen of the United States, residing at Jersey City, in the county of Hudson and State of New Jersey, have invented a certain new and useful Improvement in Game Apparatus for Playing Indoor Football, of which the following is a full, clear, and exact description.

10 The object of the invention is to provide a convenient, compact and portable apparatus for playing an indoor football game, and it is especially designed for use in presenting to its players the conditions and results that are met on a natural football field, particularly in intercollegiate football games, and to be played as though the contestants were out on the field directing the plays of their teams.

20 The invention consists of a box-like structure, the body of which is divided longitudinally by suitable partitions into alleys, each alley representing a fundamental football play, and these alleys are divided transversely by ridges projecting slightly from the bottom of the box to form spaces each of which represents the result of a particular play, the play being effected by shooting a ball in the appropriate alley, as I will proceed now to explain and finally claim.

30 In the accompanying drawings illustrating the invention, in the several figures of which like parts are similarly designated, Figure 1 is an inverted plan view of the cover of the box. Fig. 2 is a top plan view of the body of the box. Fig. 3 is a longitudinal section of the body of the box. Fig. 4 is a longitudinal section on a larger scale of one end of the body of the box.

40 The body 1 of the box is divided longitudinally by upright partitions 2 into a series of alleys 3 corresponding in number with the number of fundamental football plays common to a regular field football game and so marked in the spaces near one end of the alleys, as shown near the bottom, Fig. 2, these alleys in the instance shown being designated respectively "End run", "Line plunge", "Forward pass", "Kick" 45 and "Kick off", "Run Back", "Off tackle", "Trick play", and "Field goal". The partitions 2 are of slightly less height than the depth of the body of the box. The alleys are subdivided by means of transverse ridges 4 projecting slightly above the

level of the bottom of the box, and the subdivisions are appropriately lettered or numbered to indicate various phases of the game as it progresses. While Fig. 2 does not show all of the spaces that may or should be used to play the game, it illustrates the principle on which the layout should be made.

50 The ball 5 is propelled by any suitable means along the various alleys in accordance with the play to be made. One such propelling means is a ball rest 6 mounted on a spring 7, any suitable means being used to manipulate the ball rest and the spring in order that when the spring is compressed and then released, the ball will be propelled along the alley in which it is played.

55 In a space 8 are arranged certain counters or dials 9, 10, and 11, which are fixed to the bottom of the box, and in this same space 8 are arranged spinners 12 and 13 for use in playing the game. The dials are used to keep the contestants posted on the progress of the game, and the spinners are used when the ball stops in certain spaces, as herein-after explained.

60 The inside of the top 14 of the box is marked off to represent a gridiron or football field, as shown in Fig. 1, and a movable indicator 15 is provided to show the exact 65 yardline the ball is on after each play.

65 As in an actual football game, the players may toss a coin to decide which team shall kick off. The players then choose goals on the marked off gridiron. For the sake of 70 convenience in explaining, the player who kicks off is designated A, and the player who receives the kick is designated B.

75 Of course it is understood that the kick is made from A's forty-yard line. The ball 95 is shot down the "Kick," or as in this case, the "Kick-off" alley. Let it be supposed that the ball stops in a space marked "50." That means that B receives the ball on his own ten-yard line.

80 It is now B's turn to play the ball. He shoots the ball down the "Run back" alley. Let it be assumed that the ball stops in a "15" yard space. That means that B has run the ball back to his twenty-five-yard 100 line. It is now first down, ten yards to go.

85 B now has the choice of the following plays:—"Line plunge," "Off tackle," "End run," "Trick play," or "Forward pass."

90 It is necessary for B to make ten yards.

or more in four downs or less, and if he is successful he retains the ball, and it is again first down.

If, however, B fails to gain nearly the number of yards in three downs, it is advisable for him to kick, especially when the ball is in his own territory. Assuming that B has made only five yards in three downs, it is now his ball on his thirty-yard line, 10 and he decides to kick. Ten yards must be allowed for the distance between the ball and the punter, so that the kick is made from his twenty-yard line, instead of his thirty-yard line. Thus, if the ball stops in a space 15 marked "40," it means that A receives it on his own forty-yard line. After running the ball back, which is done after every kick, A takes his turn at carrying the ball.

If, when a player tries to kick, the ball 20 stops in the "Blocked-ball lost" space, his opponent takes possession of the ball, and is given a chance to run with it. This is done by shooting the ball down the "Run back" alley. This run is made from where 25 the ball was kicked. If the ball stops in a "No gain" or a "Fair catch" space, it is not run back at all by the player blocking it. This same rule applies to the "Fumble-ball lost" and "Intercepted" spaces. 30 If the ball stops in a "Penalty" space, the rule as applied to an actual game will be used. If the player carrying the ball is penalized, he loses the number of yards without the loss of a down. If his opponent is penalized, the player carrying the ball is given 35 a first down.

If, after a kick, the ball stops in the "Fair catch" space in the "Run back" alley, that means the player receiving does not run the 40 ball back, but puts it in play wherever he receives it.

When a player succeeds in carrying the ball over his opponent's goal line, he has scored a touchdown—six points. He must 45 then try for a goal from touchdown. This is done by shooting the ball up the alley marked "Field goal." If the ball stops at any one of the blank spaces above the space marked "10," he is successful, and scores 50 one more point.

If a player has possession of the ball between his opponent's forty-yard line and midfield, and tries for a "Field goal," the ball must stop in the space marked "50" to 55 be successful. If the ball is between the thirty-one and forty-yard lines, it must be shot in the spaces marked "40" or "50" to be successful. If it is between the twenty-one and thirty-yard lines it must stop in the 60 "30," "40" or "50" space. If it is between the eleven and twenty-yard lines, it must stop in the "20," "30," "40" or "50" space. If it is inside the ten-yard line, the ball can 65 stop in either of the five marked spaces, and the attempt will be successful. Thus it is

comparatively much easier to kick a field goal from the ten-yard line than it is to kick one from the fifty-yard line, as is, of course, the case in actual football. If the attempt fails, however, the ball goes to the 70 other player on his own twenty-yard line. A field goal counts three points.

After either a touchdown or a field goal the team scored upon has the choice of kicking or receiving. 75

If a player is forced over his own goal-line while carrying the ball, his opponent scores a safety, which counts two points. For instance, if A had the ball on his own two-yard line and tried a line plunge and 80 lost three yards, B would score two points. After a safety the team scored upon puts the ball in play on its own twenty-yard line.

The game will consist of four periods of ten minutes each, or if the players prefer, 85 each period may terminate after each player has had possession of the ball three times. At the end of the first half the ball is kicked off by the player who received at the start 90 of the game.

There are two spinners with the game. The spinner with the numbers 0—9 is used when the ball stops in the "10 or over," "20 or over," "30 or over," or "40 or over" space. The number the spinner stops on is added to 95 10, 20, 30, or 40, as the case may be. The spinner with the numbers 0—5 is used when the ball stops in a space marked "5 or over," and the numbers are added to 5. This spinner is also used when the ball stops in a 100 "50 or over" space. In this case, however, the numbers on the spinner mean ten times as much. For instance, if the spinner stops at "2," it means that twenty yards are added to the fifty, making a total gain of seventy 105 yards. Thus it is possible to go the entire length of the gridiron as is done on rare occasions in actual football.

The dials are used to keep the players posted on the progress of the game. 110

I have thus described the construction and mode of use or operation of one illustration of my invention, but it is to be understood that variations are permissible within the principle of the invention and the 115 scope of the claims following.

What I claim is:—

1. A game apparatus for playing indoor football, consisting of a number of alleys representing certain fundamental football 120 plays, and transverse ridges dividing the alleys into spaces representing the results of particular plays.

2. A game apparatus for playing indoor football, comprising a box partitioned off 125 into longitudinal alleys and these alleys subdivided into play spaces by means of transverse ridges, and means to propel a ball along the selected alley.

3. A game apparatus for playing indoor 130

- football, comprising a box having a cover marked to represent a football gridiron or playing field, and a body provided with up-standing partitions forming alleys for designated fundamental plays, and ridges intersecting the alleys transversely and dividing these alleys into spaces representing results of various plays, and means to project the ball along any of the several alleys as called for by the game. 5
4. A game apparatus for playing indoor football, consisting of a number of alleys representing certain fundamental football plays, transverse ridges dividing the alleys into spaces representing the results of particular plays, and dials for use in keeping the contestants posted in the progress of the game. 10
5. A game apparatus for playing indoor football, consisting of a number of alleys representing certain fundamental football plays, transverse ridges dividing the alleys into spaces representing the results of particular plays, dials for use in keeping the 15
- contestants posted in the progress of the game, and spinners to indicate when the ball stops in a particular space. 20
6. A game apparatus for playing indoor football, consisting of a box provided with longitudinal upstanding partitions of slightly less height than the depth of the box and serving to divide the box into alleys, and ridges standing slightly above the level of the bottom of the box and intersecting the partitions and serving to divide the alleys into particular play indicating spaces. 25
7. A game apparatus for playing indoor football, consisting of a number of alleys marked to indicate certain fundamental football plays, said alleys being subdivided into spaces marked to indicate particular plays. 30
- In testimony whereof I have hereunto set my hand this 10 day of October A. D. 1924.
